PLAYGROUND CLIMBING DEVICE

Irving A. Shepard, St. Louis, Mo., assignor to Shepard
Engineering Company, St. Louis, Mo., a corporation of
Missouri

Filed Sept. 18, 1961, Ser. No. 66,734

Term of patent 14 years

(Cl. D34—5)

FIG. 1

FIG. 1 is a perspective view of a playground climbing device showing my new design.

FIG. 2 is a cross sectional view in a vertical plane through the center of the unit shown in FIG. 1;

FIG. 3 is a cross sectional view as seen along line 3-3 of FIG. 2, and

FIG. 4 is an enlarged cross sectional view as seen along line 4-4 of FIG. 2.

I claim:

The new and ornamental design for a playground climbing device, substantially as shown.
